United States Patent [19]

Sakaguchi et al.

[11] Patent Number: Des. 315,572

[45] Date of Patent: ** Mar. 19, 1991

[54] ELECTRONIC CALCULATOR WITH
PRINTER

[75] Inventors: Hiroshi Sakaguchi; Keiichi Koyama,
both of Osaka, Japan

[73] Assignee: Sharp Corporation, Osaka, Japan

[**] Term: 14 Years

[21] Appl. No.: 210,126

[22] Filed: Jun. 23, 1988

[30] Foreign Application Priority Data

Dec. 28, 1987 [JP] Japan 62-53490

[52] U.S. Cl. D18/7; D18/2

[58] Field of Search D18/6, 7, 11, 2;
D14/100, 107, 111, 114, 115; 364/706-710

[57] CLAIM

The ornamental design for an electronic calculator with
printer, as shown and described.

DESCRIPTION

FIG. 1 is a top plan view of the electronic calculator
with printer showing our new design;

FIG. 2 is a bottom plan view thereof;

FIG. 3 is a front elevational view thereof;

FIG. 4 is a rear elevational view thereof;

FIG. 5 is a right side elevational view thereof;

FIG. 6 is a left side elevational view thereof; and

FIG. 7 is a right front and top perspective view thereof.
